United States Patent Office

Des. 233,708
Patented Nov. 26, 1974

233,708

HAMMOCK STAND

Kenneth P. Gresk, 78 Plains Apts.
Windham, Conn. 06280

Filed Mar. 12, 1973, Ser. No. 340,530

Term of patent 14 years

Int. Cl. D6—06

U.S. Cl. D6—191

FIG. 1

FIG. 2

FIG. 1 is a perspective view of a hammock stand showing my new design;

FIG. 2 is a front elevational view;

FIG. 3 is a top plan view;

FIG. 4 is a bottom plan view; and

FIG. 5 is a side elevational view.

I claim:

The ornamental design for a hammock stand, as shown and described.
